UNITED STATES PATENT OFFICE.

ISAAC H. SISSON, OF PROVIDENCE, RHODE ISLAND.

HOPPER FOR FEEDING BUTTONS, EYELETS, LACING-HOOKS, OR OTHER SUCH ARTICLES.

SPECIFICATION forming part of Letters Patent No. 549,467, dated November 5, 1895.

Application filed February 12, 1891. Serial No. 381,181. (No model.)

To all whom it may concern:

Be it known that I, ISAAC H. SISSON, a citizen of the United States, residing at Providence, in the county of Providence and State 5 of Rhode Island, have invented certain new and useful Improvements in Hoppers for Feeding Buttons, Eyelets, Lacing-Hooks, or other Analogous Articles; and I do hereby declare the following to be a full, clear, and 10 exact description of the invention, such as will enable others skilled in the art to which it appertains to make and use the same, reference being had to the accompanying drawings, and to letters of reference marked 15 thereon, which form a part of this specification.

In machines adapted for attaching to shoes, &c., shoe-buttons, lacing-hooks, eyelets, rivets, or other analogous small articles fed 20 singly from a reservoir or fountain it is very desirable that the mechanism for discharging such buttons, &c., from the hopper to the runway or chute leading to the anvil or setting mechanism be at all times both readily 25 accessible and visible.

Usually heretofore in hoppers and runways of the class referred to most if not all of the interior parts of such hoppers and runways have been concealed when in use. Sometimes 30 hoppers are provided with positively operated agitators for stirring up and separating the mass of articles therein. When thus constructed, it occasionally happens that the agitator becomes clogged, thereby rendering the machine inoperative. Meanwhile 35 the mechanism must be taken apart to make the necessary repairs or readjustment before the machine can be operated again, thereby causing considerable loss of time.

The object I have in view in the improvements forming the subject of my present invention is to overcome some of the disadvantages just named as common to hoppers heretofore made.

To that end my invention consists, essentially, of a hopper having a readily-removable transparent face and provided with an apertured movable partition which serves in a measure to separate the hopper into two 50 chambers, viz., a rear or receiving chamber and the front or distributing chamber

communicating with the former. The hopper is further provided with a mechanically-operated vibrating disk or stirrer having brushes or fingers which engage the buttons introduced into the distributing-chamber and 55 discharge them therefrom into the attached runway, the latter also having a removable transparent face. In case the traveling buttons are not properly presented to the 60 mouth of the runway the fingers automatically carry them past into the receiving-chamber to again find their way into the front chamber. The back end of the stirrer-shaft is provided with a spring-clutch, by means of 65 which the stirrer may be temporarily disconnected from the continuously-traveling mechanism when desired and independently operated by hand.

By reason of my improvements the blanks 70 or buttons are more accurately and regularly fed to the discharge-tube or runway, and in case the blanks become clogged, as may happen when freshly japanned or from any other cause, the glass-covered or transparent face 75 of the hopper and runway enables the attendant to readily locate the trouble, when frequently a slight jarring at the point or possibly a few turns of the stirrer by hand, after withdrawing the clutch, will remove the cause 80 of the interruption without the necessity of taking the mechanism apart.

In the appended two sheets of drawings, Figure 1, Sheet 1, is a front elevation of my improved hopper and runway. Fig. 2 is a vertical sectional view taken on line *m m* of Fig. 1. Fig. 3 is a horizontal sectional view of the runway, taken on line *x x* of Fig. 1. Fig. 4, Sheet 2, is a front view of the hopper, showing the relation of the brushes, &c., as opposed to the position represented in Fig. 1. Fig. 5 is a side elevation showing the clutch withdrawn, and Fig. 6 is a front view of the movable partition detached.

I would state before proceeding farther 95 with a detailed description of my invention that the latter is not limited to any particular machine provided with means for attaching the buttons, hooks, blanks, or other articles. Therefore I have deemed it unnecessary to represent a machine of such class complete, it being a common and well-known 100

method to automatically receive buttons, &c., singly from the mouth of a runway and attach them to leather or other suitable material. I would add, however, that an improved button-attaching machine combined with my present improved hopper and runway will form the subject of another application for United States Letters Patent about to be filed by me.

10 My improved hopper as a whole is indicated by A and the runway by B. The hopper, &c., as drawn is supported by a hollow standard e' , secured, say, to the table or base x of a suitable machine. One side of the standard is slotted, through which extends a head i' of the toothed rack i , the latter being mounted to reciprocate vertically in the standard by means of a suitable reciprocating link i' , jointed thereto by a pin i^2 .

15 The hopper-frame b is provided with a central hub which is bored out to receive a stirrer-shaft g . The rear portion e of the hopper is made hollow to receive the rack i and is secured to and forms a continuation of the standard. A small toothed wheel h is loosely mounted upon the shaft g . The wheel revolves in a housing e^2 (shown by dotted lines, Fig. 1) of the said rear portion e and intergears with the rack-teeth. The hub of the wheel

20 h extends through the rear wall of the housing and is notched, as at n' , to receive a lug n , Figs. 2 and 4, of the spring-clutch k , the latter being fitted to slide endwise upon a key m , seated in the shaft g . A spring l , bearing against the adjacent faces of the clutch, and a collar g' , secured to the outer end of the shaft, serve when normally working to maintain the gear-wheel in clutch.

25

30 At the top of the hopper-frame is placed a receiver a , communicating with the throat-opening a' of the hopper. This opening conducts the blanks directly into the receiving-chamber c , from whence they issue via the opening p' into the front or distributing chamber c' . The interior of the hopper is formed into two chambers $c c'$ by means of the thin plate or partition p , the latter being substantially semicircular in shape and having an opening p' at the bottom and notches p^2 at the upper ends of the plate. (See Fig. 6, &c.) The face of the hopper is made preferably circular in form and is recessed to receive the front or covering plate t , of glass or other suitable transparent material. Spring-pins t' having flattened heads hold the cover in place. The stirrer-disk d is secured to the shaft by a screw g^2 , the hub of the disk as drawn passing loosely through the partition-plate p . It will be seen that the depth or thickness of the front chamber c' is or may be the same or slightly greater than the blank across its largest diameter. By this means the blanks are kept in substantially the same plane while being acted upon by the fingers f^2 of the stirrer. In case buttons s are to be fed to the runway I, preferably form a circumscribing groove c^2 in the hopper adja-

cent to the front, the form of the groove being such that the head of the button will rest fairly therein, the shank s' at the same time being also guided. (See Fig. 2.)

The runway B is fitted to an opening m^2 , formed at the right in the face of the hopper and communicating with the chamber c' , a dowel-pin (k^2 shown by dotted lines) serving to attach and hold the parts together. The front or face of the runway is made of glass t^2 or other suitable transparent material, a spring-pin w , having a notched head w' , Fig. 3, in conjunction with adjustable guides or lugs v , acting to retain the cover in place. The runway is provided throughout its length with a front chamber u , communicating with a narrow vertical groove or slot u' , formed at the back. The heads or fronts of the buttons s are introduced into the front chamber u , the shanks or eyes s' at the same time being guided by the rear groove u' . By this arrangement the buttons are received singly from the hopper by means of the moving brushes f^2 and fall by gravity to the mouth of the runway, from which they are checked off by suitable means. As mechanism for this purpose forms no part of my present invention, I have considered it unnecessary to indicate a checking device.

The operation is as follows, assuming, first, however, that the apparatus is adapted, say, to receive and feed shoe-buttons s , and that a reciprocating movement is imparted to the rack i . Now upon depositing buttons into the receiving-chamber c some of them immediately enter the front chamber c' by means of the opening p' , formed in the loose partition-plate p . These are picked up or carried along by the fingers f^2 , Fig. 4, and some or all of the buttons that have assumed a proper position are brushed into the runway, others being carried upwardly and over the top edge of the plate. The brushes are so arranged in the disk d that upon the return stroke (Fig. 1 shows the commencement of such stroke) any remaining buttons held by them will be brushed into the runway or carried back to the bottom of the chamber, the latter being supplied with buttons from the reservoir or rear chamber c , as before stated. During the reciprocations of the brushes back and forth in the distributing-chamber, any tendency of the buttons to become clogged or "bridged" is immediately corrected by the plate p , because the pressure of buttons at the back causes it to frictionally engage and be carried axially back and forth by and in unison with the disk d ; but such axial movement of the plate is quite limited, (see Figs. 1 and 4, which represent the extreme positions,) stationary stops c^4 being used to limit the plate's movement.

When the device is employed for feeding other articles than the buttons shown, obviously the form of the rim of the distributing-chamber transversely and the interior of the runway should be modified correspondingly.

The mechanism represented is well adapted to be employed independently of any attaching or setting machine—as, for example, the runway itself may be readily removed when 5 filled, an empty one being substituted therefor and the operation continuously repeated, thereby using the machine simply for filling the tubes B, or the runway may be adapted to receive at its lower end tubes or magazines 10 which are removed as fast as filled, the same forming practically a continuation of the runway itself. As drawn, the lower end of the runway is provided with a spring stop or check w², which serves to prevent the buttons 15 from falling out. I make no claim, however, to any specific form of stop.

I claim as my invention—

1. A hopper having a receiving chamber and a front or distributing chamber, a runway 20 communicating with the latter chamber, loose plate or apertured partition capable of an oscillating movement separating said chambers, and a stirrer mounted to rotate or oscillate back and forth in the distributing 25 chamber.

2. The combination in a hopper, of a loosely mounted apertured partition capable of an oscillating movement, stops for limiting such movement, a stirrer mounted in front of and 30 contiguous to said partition, mechanism for oscillating the stirrer back and forth, and a suitable runway communicating with the hopper, substantially as hereinbefore described.

3. The combination of a hopper provided 35 with a cover through which the interior of the hopper-chamber may be seen, a runway communicating with the hopper-chamber provided with a suitable cover, a stirrer mounted 40 in the hopper-chamber, mechanism for actu-

ating the stirrer in an oscillatory manner, an apertured partition located at the back of the stirrer and forming a front chamber, as c', between the adjacent faces of said partition and the hopper cover, and means for connecting the stirrer with and disconnecting it from the driving mechanism, substantially as described. 45

4. The hopper, substantially as hereinbefore described, provided with the front or covering plate t, a runway communicating with the hopper having a covering plate t² and provided with a stop at its lower end for holding the column of buttons in check, an apertured partition adapted to divide the interior of the 50 hopper laterally into receiving and distributing chambers, a stirrer mounted between the adjacent faces of said hopper-cover and partition, driving mechanism for actuating the stirrer, and a slip-clutch adapted to lock the 55 stirrer to or disconnect it from said driving mechanism, all combined and adapted for operation, substantially as hereinbefore described.

5. In a hopper provided with a stirrer and 60 a sliding spring-clutch located on and revolving with the stirrer-shaft, the combination therewith of a guided gear-wheel loosely mounted on the stirrer-shaft arranged to interlock with said clutch, and a toothed rack 65 engaging the gear-wheel, whereby an oscillating movement is imparted to the stirrer upon reciprocating the rack back and forth, substantially as hereinbefore described.

In testimony whereof I have affixed my signature in presence of two witnesses.

ISAAC H. SISSON.
